(57) **CLAIM**

The ornamental design for a five valve manifold with angle bonnet, as shown and described.

DESCRIPTION

FIG. 1 shows a perspective view of a first embodiment of the invention; and,

FIG. 2 shows a perspective view of a second embodiment of the invention. The dotted lines do not form part of the patented design.

The broken lines showing portions of the handle of the five valve manifold with angle bonnet form no part of the claimed design. The broken line showing of the hole members of the five valve manifold with angle bonnet represents an unclaimed boundary line and forms no part of the claimed design.
